CASEMENT WINDOW

Albert Lang, Berkeley, Calif.

Application September 24, 1934, Serial No. 745,225

3 Claims. (Cl. 292—138)

This invention relates to a casement window structure and more particularly to one having a fabricated metal sash and window frame with a mechanical actuating means for controlling the movements of the sash between its opened and closed positions.

An object of the invention is to provide a locking means for the free edge of a sash of the above character which will operate, in conjunction with the sash actuating means at one end of the sash, to draw and hold the free edge of the sash into the frame when the sash is moved into its closed position by said actuating means.

Another object of the invention is to provide a locking means for a fabricated metal sash of the out-swinging type which will be concealed from view when the sash is in its closed position.

When sashes of the character contemplated by this invention are made of iron they must, in order to reduce the total weight thereof, be fabricated with structural iron sections of special design. Therefore, the frame and sash are usually made of structural iron having a modified Z cross section. Structural iron of such a cross section provides a very rigid sash and frame where the window is of a small size but, where the size of the window is increased beyond a definite limit the sash becomes flimsy and has a tendency to become distorted and sometimes sags so that the free edge and top thereof cannot be drawn into tight antirattling engagement with the frame at these points by the forces applied, at the bottom of the sash, by the actuator. In the past it has been the practice to provide an additional lock or latching means, which is operated independently of the actuator, for tightly closing the sash upon the frame in a satisfactory manner. However, when an inside screen is used with such an out-swinging sash it is difficult, if not impossible, to mount a separate latch or locking means upon the sash so that it can be operated without removing the screen. It is, therefore, a further object of the present invention to provide a latching means which will operate with the sash actuator to draw and lock the sash snugly within the frame, at a point remote from the sash actuator, in response to forces exerted upon the sash by the actuator.

With the above and other objects in view, the invention resides in the construction, combination and arrangement of parts substantially as will be hereinafter described and more particularly defined by the appended claims.

For a better understanding of the invention reference should be had to the accompanying

drawing wherein there is shown, by way of illustration and not of limitation, a preferred embodiment thereof.

In the drawing:

Figure 1 is a perspective view of a frame and sash assembly of the type contemplated by this invention.

Figure 2 is a fragmentary vertical sectional view with parts broken away to show the details of construction.

Figure 3 is an enlarged fragmentary view, with the sash nearly closed, looking toward the inside of the frame, as indicated by arrow A in Figure 1, with parts broken away to disclose the details of construction, and

Figures 4 and 5 are fragmentary views of a modified detail of the invention.

In the drawing the numeral 10 designates a casement window frame and the numeral 11 designates an out-swinging sash which is hinged upon the frame 10 by means of outwardly disposed hinge forming brackets 12. The window frame 10 and the sash 11 are constructed of rolled structural iron having a substantially Z-shaped cross section and the frame is made slightly larger than the sash so that the latter will nest snugly within the frame. A sufficient clearance is provided between the frame 10 and the sash 11 to accommodate a sash actuating means and a locking means of the type contemplated by this invention when the sash is in its closed position.

The sash 11 is adapted to be moved into its opened and closed positions by means of an actuator 13 which in the present instance is shown, for the purpose of illustrating one type, as comprising a pivoted arm 14 having a rack sector 15 which is engaged by a worm gear (not shown) that is controlled by an operating crank 16.

The outer end of the arm 14 slidably engages a suitable recess extending along the bottom of the sash 11 and when the crank 16 is turned the sash 11 will be moved by the arm 14 as it pivots in response to forces applied to its rack sector 15, by the worm gear of the actuator 13, when the operating crank 16 is turned.

The embodiment of the present invention which has been chosen for the purpose of illustration comprises a locking bar 17 that is slidably mounted upon the web of the Z-shaped section forming the free edge of the sash 11. The locking bar 17 has a slot 18 at its top and bottom ends through which a screw 19 passes. Intermediate the ends of the locking bar 17 there is an additional slot 20 with an adjustable pin 21.

disposed therein for properly positioning the locking bar 17 upon the sash 11 and limiting its downward movement. At its upper end the locking bar 17 has an offset extension 22 that is 5 adapted to engage an abutment or keeper 23 which is secured upon the inner cheek of the window frame 10 and at its lower end the locking bar 17 has an anti-friction roller 24.

The screws 19 are so positioned upon the sash 10 that they will support the locking bar 17 with the roller 24 extending slightly below the sash 11 when the latter is out of engagement with the frame 10. This will permit the locking bar 17 to be moved upwardly, when the roller 24 engages 15 an inclined surface or stationary cam 25 carried by the frame 10, and bring the offset extension 22 thereof into interlocking engagement with the abutment or keeper 23 carried by the frame 10.

As shown in Figure 2 of the drawing, the offset 20 extension 22 and the keeper 23 have inclined surfaces which will cooperate, during the final closing movement of the sash 11, to draw the free edge of the sash 11 into close engagement with the frame 10 at a point remote from the actuator 25 13.

In practice, it is desirable to provide a maximum of clearance between the lower end of the keeper 23 and the upper end of the offset extension 22 so that there will be no danger of interference between these parts, before the roller 24 30 comes into its operative position upon the inclined surface 25 at the bottom of the frame 10. However, because of the limited movement of the sash 11 with respect to the frame 10 during the final closing operation, this clearance cannot be 35 excessive. To regulate the clearance and properly position the abutment or keeper 23 with respect to the inclined surface 25 at the bottom of the frame 10, the abutment or keeper 23 is adjustably secured upon the cheek of the frame 10 by means 40 of screws 26.

As shown in Figure 3 of the drawing, the inclined surface 25 is made comparatively steep at its initial roller engaging end. This will cause the roller 24 to raise rapidly and move the locking bar 17 upwardly to take up the clearance and bring the inclined surface upon the offset extension 22 into cooperating relation with the inclined surface upon the abutment or keeper 23 before the sash 11 is fully closed. At this point the remaining portion of the inclined surface 25, which is disposed at a considerably less inclined angle, will offer very little resistance to the final closing of the sash 11 by the actuator 13. The angle of inclination of this latter portion of the surface 55 25 is such that it will, with little effort, when the keeper 23 is properly positioned, forcefully move the locking bar 17 upwardly a sufficient distance to produce a wedging action between the cooperating inclined surfaces upon the offset extension 60 22 and the keeper 23 and draw the free edge of the sash 11 tightly into the frame 10 as the actuator 13 draws the bottom of the sash 11 into the frame 10.

In Figures 4 and 5 of the drawing, there is 65 shown a modified arrangement of the invention wherein a locking bar 27 is adapted to be operated by a bell crank which is mounted upon a pivot 28 at the lower part of the sash 11. As here shown, the bell crank has a relatively long downwardly projecting arm 29 and a short arm 30. The long arm 29 of the bell crank has an inwardly extending end 31 which is adapted to engage the frame 10 before the sash 11 reaches its final closed position and the short arm 30 of the bell 70 crank is pivotally connected to the lower end of

the locking bar 27. This arrangement, with a bell crank having a long arm 29 and a short arm 30, as described above, provides for an increase in leverage which will produce a forceful wedging action between the locking bar 27 and its cooperating abutment without producing a corresponding resistance to a final closing of the sash 11 by the actuator 13.

The operation of a sash constructed in accordance with this invention, in so far as the opening and closing movements thereof are concerned, should be evident from the above. However, in order that there will be no misunderstanding as to the final closing and locking operation of the locking bar 17, it may be said that when the bottom of the sash 11 is moved by the actuator 13 into a position approaching its final closed position the roller 24 will engage the inclined surface 25. This will cause the locking bar 17 to move upwardly and, when the keeper 23 is 20 properly adjusted with respect to the inclined surface 25, bring the cooperating inclined surfaces upon the offset extension 22 of the locking bar 17 and upon the keeper 23 into engagement so as to produce a wedging action which will draw the sash 11 inwardly at this point and lock it firmly in the frame 10. The operation of the modified form of the invention shown in Figures 4 and 5 of the drawing is similar to the above except that, instead of the roller 24, there is 30 the extension 31 upon the long arm 29 of the bell crank which engages the frame 10. The extension 31 projects inwardly from the sash 11 a sufficient distance to engage the frame 10 before the sash 11 has completed its closing movement. This 35 causes the bell crank to rotate upon its pivot 28 and lift the locking bar 27 upwardly to produce the wedging and locking action above described.

When the sash 11 has been closed and locked in the above manner, it will be held firmly and 40 tightly closed upon the frame 10 until the actuator 13 is operated to move the sash 11 from its closed position. Upon a sash opening operation of the actuator 13, the bottom of the sash 11 will be moved outwardly and as a result the roller 24 45 will move downwardly over the inclined surface 25 and permit the cooperating surfaces upon the offset extension 22 and the keeper 23 to disengage. The sash 11 can then be fully or partially opened by the actuator 13.

There may be instances where it will not be feasible, because of climatic conditions, to mount the locking bar 17 upon the sash 11. In such instances the parts, which comprise the locking bar 17, the keeper 23 and the inclined surface 25 55 and their accessories, can be reversed in position upon the window sash and frame. Under these conditions the locking bar 17 will be mounted in a reversed position upon the frame 10 and the keeper 23 and the inclined surface 25 will be 60 mounted upon the sash 11. In this arrangement the roller 24, upon the lower end of the locking bar 17, will be raised as the bottom of the sash 10 with the inclined surface 25, now carried at the bottom of the sash, is drawn in under the 65 roller 24 by a sash closing operation of the actuator 13. This will bring the inclined surfaces upon the offset extension 22 and upon the keeper 23 into cooperating relation and lock the sash 11 in the manner above described.

By way of illustration, I have shown the locking bar 17 as a flat slideable bar, but it is to be understood that this bar may take other forms. For instance, it may be a round rod having offset ends which will properly engage abutments upon 70 75

the frame and sash and rotate in its operation to draw in and lock the sash as contemplated by this invention.

While I have, for the sake of clearness and in order to disclose my invention so that the same can be readily understood, described and illustrated specific devices and arrangements, I desire to have it understood that this invention is not limited to the specific means disclosed, but may be embodied in other ways that will suggest themselves to persons skilled in the art. It is believed that this invention is new and it is desired to claim it so that all such changes as come within the scope of the appended claims are to be considered as part of this invention.

Having thus described my invention my invention, what I claim and desire to secure by Letters Patent is—

1. In a casement window structure, the combination of a skeleton frame of metal having hinges at one side thereof, a sash formed of metal having a channel cross section mounted upon said frame, hinges and swingable with respect to said frame, an adjustable keeper upon said frame in the sash opening and disposed opposite the hinges carried thereby, said keeper having an outwardly and downwardly inclined detent receiving surface, a slidably mounted bar disposed along the free edge of said sash and in the channel thereof having an inwardly and upwardly inclined detent forming surface at its upper end adapted to engage said keeper, means forming an outwardly and downwardly inclined surface upon said metal frame disposed in line with the bar upon the free edge of the sash, the surface upon said means having two inclinations, the first of which is at a slight angle from vertical and the second of which is at a slight angle from horizontal, a roller disposed in an inward position upon the lower end of said bar adapted to engage the inclined surface upon said frame and move said bar so as to cause the detent forming surface at the upper end of said bar to engage in wedging relation with the inclined surface upon said adjustable keeper during the final operation of the sash, and means for vertically adjusting the position of said keeper upon said frame.

2. In a casement window structure, the combination of a skeleton frame of metal having hinges at one side thereof, a sash formed of metal having a channel cross section around its outer

boundary mounted upon said hinges and swingable with respect to said frame, a keeper upon said frame disposed in the sash frame opening opposite the hinges carried thereby, a slidably mounted locking bar extending along and carried by the free edge of said sash, said slidably mounted locking bar having a keeper engaging end adapted to cooperate with said keeper, a locking bar engaging member mounted upon the sash frame below said keeper having a double inclined surface projecting into the sash opening of said frame where the lower end of said slidably mounted locking bar will engage same, the double inclined surface of said locking bar engaging member being adapted to first move said slidably locking bar a substantial part of its movement to bring its keeper engaging end into interlocking relation with the keeper upon said frame and during the final closing operation of the sash to move said slidably locking bar the remainder of its movable distance to effect a final locking of the sash upon said frame.

3. In a casement window structure, the combination of a skeleton frame of metal having hinges at one side thereof, a sash formed of metal mounted upon said hinges and swingable with respect to said frame, a keeper carried by said frame disposed in the sash opening opposite the hinges carried thereby, a locking bar carried by and slidably mounted upon the free edge of said sash, said slidable sash locking bar having means at its upper end adapted to engage said keeper, a locking bar operating member secured upon said frame below said keeper having an outwardly projecting double inclined surface projecting into the sash opening upon said frame and disposed in the path of the lower end of said locking bar, the outermost incline of said double inclined surface being relatively steep with respect to the horizontal and the innermost incline thereof being less steep, and means upon the lower end of said locking bar adapted to engage the inclined surfaces upon said operating member, whereby said locking bar will be first moved a major distance to bring its keeper engaging end into interlocking relation with said keeper and during the final closing operation of the sash to be moved a minor distance into full sash locking relation with said keeper.
